H. DREYFUS.

MANUFACTURE OF ACETIC ALDEHYDE.

APPLICATION FILED JUNE 1, 1917.

1,310,743.

Patented July 22, 1919.

UNITED STATES PATENT OFFICE.

HENRY DREYFUS, OF BASEL, SWITZERLAND.

MANUFACTURE OF ACETIC ALDEHYDE.

1,310,743

Specification of Letters Patent. Patented July 22, 1919.

Application filed June 1, 1917. Serial No. 172,325.

To all whom it may concern:

Be it known that I, HENRY DREYFUS, of Basel, Switzerland, have invented certain new and useful Improvements in or Relating to the Manufacture of Acetic Aldehyde, of which the following is a specification.

This invention relates to the manufacture of acetaldehyde from acetylene by passage 10 of acetylene into an absorbing solution containing a mercury compound and sulfuric acid.

The manufacture of acetic aldehyde is of 15 particular importance in view of its employment for transformation into acetic acid. This manufacture of acetic acid is only interesting industrially if the acid can be produced at a low price which can compete with the processes hitherto employed, such as the 20 acetate of lime process. The problem of manufacturing acetaldehyde by processes of the character indicated is very difficult, both as regards providing a process capable of producing acetaldehyde economically on a 25 large scale, and as regards providing apparatus which will allow of such a manufacture.

The chief difficulty in regard to apparatus is due to the employment of mercury or its 30 salts or compounds, as these amalgamate with all metals except iron, so that these metals cannot be used. Iron itself cannot be used for the apparatus, owing to the employment of acids in the process, which attack 35 iron and precipitate the salts of mercury even before the acetylene is introduced, and therefore before formation of the acetic aldehyde.

In the present invention there has been 40 found a process of manufacture of acetic aldehyde from acetylene, which fulfills the essential conditions above referred to. I have also succeeded in overcoming the difficulty in regard to apparatus and have found 45 means as hereinafter referred to but forming the subject of another application (Serial No. 229,174, filed April 17, 1918, being a division hereof) of providing apparatus permitting of the industrial realization 50 of the process.

The new process will be first described

and the apparatus to be employed will be described further on.

The process of manufacture.—The aim of my present process of manufacture is to produce per kilo of mercury salt or compound employed in one operation before recovery 55 of the mercury, the greatest possible amount of acetic aldehyde and without the production of crotonic aldehyde or other condensation products which have no value for the manufacture of acetic aldehyde.

The question of whether the yield of acetic aldehyde based upon the quantity of acetylene introduced approaches the theoretical 65 is a matter of secondary importance as compared with the question of whether a given amount of mercurial catalyst can be made to produce a large yield of acetic aldehyde before it becomes exhausted.

According to the present process therefore one is not content only to say for example that the yield of acetic aldehyde or crotonic aldehyde, etc., is almost quantitative, or is 50% or 80% or 90% or theoretical, relative 75 to the quantity of acetylene introduced; for even if the yield of acetic aldehyde, alone or with crotonic aldehyde, etc., were theoretical, relative to the quantity of acetylene introduced, and the quantity of acetic aldehyde obtained were only the same as or even double the quantity of oxid of mercury or salt of mercury employed, this result would 80 not be of commercial interest.

With the present invention one can obtain 85 yields of acetic aldehyde amounting in weight to from five to ten or more times the weight of the mercury compound employed, or even fifteen to twenty times this weight.

The result in view is only obtained by observing a large number of conditions, all of which must be followed, for each of them assists in obtaining a large yield such as above indicated.

These conditions are as follows:—

(I). The amount of sulfuric acid used must be between about 10% and about 15%, of the weight of the absorbing solution. This amount provides for the presence of 100 free sulfuric acid in the solution.

(II). The oxid or other compound of mer-

cury used in the solution is employed in an amount corresponding to 1 to 10 per cent. of metallic mercury, and preferably between about 3 and 6 per cent. of metallic mercury, based on the weight of the absorbing solution.

(III). A temperature not exceeding 40° C., and preferably between about 25°-40° C., is observed during the introduction and absorption of the acetylene.

(IV). The acetylene is introduced in a slow current at the beginning, until the mercury compound in the absorption liquid has become gray or grayish black, which indicates that the solution has reached about its maximum absorbing power, the acetylene being then introduced as rapidly as possible, while avoiding excess and non-absorption.

(V). Strong agitation is maintained during the introduction of the acetylene, so as to secure intimate mixture thereof with the absorption liquid.

(VI). The acetaldehyde formed is distilled off at intervals by raising the temperature, but not above about 50°-60° C., the temperature being reduced to the lower temperature set forth under (III) for the re-introduction of the acetylene, the operations of acetaldehyde production and distillation being repeated in alternation, as many times as required.

The acetylene is preferably introduced under a super-atmospheric pressure of about half an atmosphere.

When the absorbing power of the solution has diminished considerably or ceased in the course of the repeated absorptions and distillations, the solution may be heated above 60° C. to distil off remaining traces of acetaldehyde.

The oxid or compound of mercury employed should be entirely dissolved in the absorption liquid before introducing the acetylene. This may be effected by heating the liquid containing the mercury compound to dissolve the same, the liquid being then cooled to the appropriate temperature for the introduction of the acetylene.

The acetylene should be freed from its impurities, such as sulfureted hydrogen, phosphoreted hydrogen, or ammonia, before introduction into the solution.

It must not be attempted to convert the acetaldehyde into acetic acid by simultaneous oxidation with an oxidizing agent as it is formed, because this would prevent the reduction of the mercury compound to the active form referred to, and the increase of the concentration of the acid, as acetic acid was formed, would disturb the equilibrium in the conditions necessary to arrive at the industrial result.

The hydration of acetylene by sulfuric acid was studied by Berthelot (see for example *Annales de Chimie et de Physique*

1863, Series 3, Vol. 67, p. 56 *et seq.*) and the production of acetaldehyde by such hydration was studied by Béhal (*Annales de Chimie et de Physique* VI. Vol. 15 page 268 *et seq.* and VI. Vol. 16 p. 376 *et seq.*) and by Lagermarck and Eltekoff (*Berichte der deutschen chemischen Gesellschaft* Vol. X, p. 637 *et seq.*).

According to Kutscherow's process (*Berichte* Vol. XVII page 13) as applied to acetylene, acetaldehyde is produced, the said process consisting in forming a compound of the acetylene with bichlorid, sulfate or acetate of mercury and decomposing the resulting product with water (*Annales de Chimie et de Physique* VI. Vol. 15 page 268).

Erdmann and Köthner effected the manufacture of acetic aldehyde from acetylene in 1898 (*Zeitschrift für Anorganische Chemie*, Vol. 18, 1898, page 55) by passing a current of acetylene through a heated liquid containing oxid of mercury and about 40 per cent. of sulfuric acid. In working according to this process the intensive absorption of the acetylene causes much acetic aldehyde to distil, while another part of the acetylene introduced is transformed into condensation products such as crotonic aldehyde, etc. During the introduction, the liquid, after a certain time, becomes colored more and more, and at length becomes quite dark, and little by little the absorption of the acetylene diminishes, and finally ceases altogether. In view of this fact, others have employed the same liquid containing oxid of mercury with 45 per cent. of sulfuric acid, at lower temperatures, below 50° C. and especially 15° to 30° C., but the result is unsatisfactory on account of the very great condensing action of the sulfuric acid of 45%, which forms at once crotonic aldehyde and resins, and because of the cessation of the absorption.

French Patent No. 474,246 of 29 June 1914 uses a high temperature of 50 to 70° C. with a high concentration of the acid, to cause the acetic aldehyde formed to escape the condensation.

According to French Patent No. 360249 of 17 February 1905 only a restricted quantity of acetic aldehyde is obtained. Likewise in the *Berichte* 42 (2) 1909 page 2759 Kutcherow has described a process analogous to his previous process, employing zinc and cadmium salts instead of mercury compounds.

The best hitherto proposed processes, from the standpoint of the results obtained, are those of British Patents 6000 of 11 March, 1913, 16848 of 22 July 1913, 17017 of 24 July 1913 and 16957 of 17 July 1914.

In the process of British Patent No. 6000/1913 there is employed a temperature above 70° C. and a very restricted quantity of sulfuric acid, not exceeding about 6 per

cent. in acid, (according to the example page 2 even $3\frac{1}{2}$ per cent. of acid), just about sufficient to convert the oxid of mercury into sulfate of mercury.

5 In that process it is intended for the aldehyde to evaporate as soon as formed, in order to escape condensation which latter is also diminished by the small percentage of sulfuric acid.

10 With my process, as compared with this process, the temperature is maintained below 40° C. during the introduction and absorption of the acetylene, and the percentage of total sulfuric acid in the solution is not 15 less than 10 per cent. and not more than 15 per cent., the best absorption and yield being obtained between about 25° or 30° and 20 40° C. At substantially higher temperatures such as indicated in the English Patent 6000/1913 the acetaldehyde-producing power of the oxid or compound of mercury is much less, the acetylene then acting materially to render the mercury compound more inactive for the absorption of acetylene, and forming mercurial condensation products, probably carbids of mercury, polymerized and inactive. On the other hand 25 the limits of 10 and 15 per cent. total sulfuric acid are observed in the present invention. I have found in fact that in employing free sulfuric acid in the solution, the amount of free sulfuric acid being however, as an important principle, within certain low limits, one can attain not only five 30 times the weight in acetaldehyde of the weight of the oxid of mercury employed, but 35 8 to 10 times or 15 to 20 times as much as the weight of the oxid of mercury or salt of mercury employed, and on the other hand 40 I have found that if sulfuric acid is only used in a quantity such that it is just sufficient to make the sulfate of mercury, the yield is much less, but that the yield will be improved in proportion to the increase of 45 the free sulfuric acid beyond this amount, while keeping within the limits of 10% and 15% total acid before mentioned. At higher concentrations the amount of condensed products incapable of use for the manufacture 50 of acetic acid gradually increases with the increase of concentration of the acid, and with an absorbing solution containing 40 per cent. or more of sulfuric acid it takes only a short time of contact for all the acetic 55 aldehyde to be converted into crotonic aldehyde.

I have found that, with whatever concentration of sulfuric acid, the best absorption, with the best yield, always occurs at temperatures of about 20° to 40° and preferably about 25° or 30° to 40° C.

The acetic aldehyde formed in my process is removed by distillation at desired intervals, the absorption being then recommenced 60 after lowering the temperature to the proper

figure as above mentioned. It is very important to cease the introduction of the acetylene during the distilling operation, because at a raised temperature the acetylene would render the salts or compounds of mercury inactive much more rapidly, so that the total yield of acetic aldehyde would be reduced. Moreover for the distillations the temperature must not be raised too much (not above about 50° - 60° C.), because by 70 raising the temperature to 80° C. for example, the yield of acetaldehyde is greatly prejudiced. Nevertheless toward the end of the working, the temperature can be raised to 80° to 100° C. to drive off the acetaldehyde from the liquid as completely as possible. 75

Working as above described the acetylene can be introduced with the greatest possible rapidity into the absorption liquid, a point which is of very great importance, because the rapid introduction of the acetylene, naturally with complete absorption without excess, also assists in producing, with a certain given weight of oxid or compound of mercury, the largest multiple of this weight in acetic aldehyde. For the yield of acetic 80 aldehyde in relation to the weight of oxid or compound of mercury employed diminishes in proportion to the prolongation of 85 the introduction of the acetylene, since the oxid or compound of mercury used becomes 90 more and more inactive.

There has always been obtained in the process, as herein described, a residue of the 100 mercury compound employed, consisting of a gray or dark gray powder, with a yellowish or brownish tint, this tint varying in accordance with the percentage of acid employed. 105

The greater part of this powder containing metallic mercury represents a mercury derivative of acetylene, perhaps of high polymerization, which by treatment with any oxidizing agents, say by chlorin or 110 nitric acid, or by a mixture of hydrochloric and nitric acids, or by peroxids in presence or absence of acids, or by persulfates or percarbonates or by electrolytic oxygen or by sulfuric anhydrid or by fuming sulfuric 115 acid (oleum) or by carbonate of soda can be transformed for its regeneration into the corresponding salt or compound of mercury.

In the processes described in British Patents No. 16848 of 1913, 17017 of 1913, 16957 120 of 1914 and French Patent No. 474246 already referred to, it is proposed to introduce the acetylene in excess, so that the unabsorbed acetylene acts as a vehicle for the acetic aldehyde formed.

With the present invention it is essential that only the quantity of acetylene capable of being absorbed shall pass through the reaction liquid; this is to preserve in the salt or compound of mercury the highest power 130

of production of acetic aldehyde in relation to the employed weight of the salt or compound of mercury, as excess of acetylene rapidly renders the salt or compound 5 of mercury inactive.

In the said French Patent No. 474246 the excess of acetylene introduced is to replace 10 mechanical agitation. This is impossible in the present invention, as it is important that agitation shall be employed, while avoiding excess of acetylene.

Further, the quantity of oxid of mercury or salt or compound of mercury contained in the absorption liquid is of essential importance 15 for the present invention. I have found that even if all the other conditions before mentioned (I, III, IV, V and VI), are observed, a very poor yield is obtained on employing large quantities of mercury salt or compound in an absorption liquid, as relatively little acetic aldehyde is formed. For example by employing in an absorption liquid 3 to 4 kilos of sulfate or other compound of mercury to 10 liters of 20 dilute acid of 15 per cent., there is only obtained, notwithstanding the absorption of the acetylene at the commencement, say about the same weight of acetaldehyde as the weight of the mercury compound used, 25 or it may be up to about double this weight.

In proportion as the quantity of mercury compound, calculated on the quantity of the absorption liquid is diminished, the other conditions above set out being observed, the 30 quantity of acetic aldehyde produced will increase, but on the other hand the quantity of mercury compound must not be taken too low as the absorbing power would then diminish too much, so that the industrial manufacture would be impossible or prejudiced. I employ not more than about 10% and preferably between about 3% and 6% of mercury compound calculated on the 35 weight of the absorption solution.

40 The oxid or compound of mercury employed should be dissolved completely in the absorption liquid before the introduction of the acetylene. This would not be possible if an absorption solution were employed 45 containing no free sulfuric acid (*i. e.* supposing only enough acid to be used to combine with the oxid of mercury) or only 3 to 5 per cent., and the result would be a relatively poor yield of acetic aldehyde, as in 50 such case the oxid of mercury or the sulfate of mercury does not dissolve or only dissolves partially in the absorption liquid before the absorption of the acetylene; for this 55 reason while keeping within the limits before mentioned, sufficiently more acid is necessary in order that the mercurial substance or compound may be dissolved.

The reason for this lies in the fact that in introducing the acetylene into the ab-

sorption liquid there is formed after a certain time a precipitate representing a compound of acetylene with the mercury body which, in this way, gives the greatest possible surface to the acetylene introduced, serving as a contact agent, so that the greatest possible absorption is thus insured. 65

It must not be thought however, that the absorption is immediately intense the moment the acetylene is introduced. For it has been found that during a certain time 70 the absorption of the acetylene introduced is very slight, and this may even last for an hour, or up to several hours or more, according to the composition of the absorption liquid, and only increase after the voluminous precipitate produced by the acetylene introduced becomes more and more dark, or rather grayish-black, reaching the maximum absorbing power then. It is only then 75 that the real contact substance begins to produce its effects, as shown by the fact that the acetylene can be introduced abundantly 80 at the same time being absorbed whereas before this state of color of the mercurial precipitate is reached only a very weak current of acetylene can be introduced and absorbed as otherwise the acetylene passes through without entering into reaction. 85

90 Based on these observations it is believed that it is carbide of a lower oxid or oxids of mercury which is formed and serves as a contact substance, since it has been found that on passing acetylene through a liquid containing mercurous sulfate, the same black or black-gray precipitate is formed 95 having the same properties as the product obtained after the introduction of the acetylene during a relatively long time into a solution containing a mercuric salt. 100

105 Proposal has heretofore been made to convert the acetylene first into acetaldehyde and to convert this latter into acetic acid, all in one operation, by introducing a mixture of acetylene and an oxidizing gas, into a solution containing a mercury compound. The 110 failure of such process, I believe, is caused by the fact that the first reaction referred to requires, as a catalyst, a mercurous compound, and by the introduction of the oxidizing gas the formation of this black or 115 grayish-black precipitate, capable of effectively acting as the catalyst, was prevented. It will be seen that the formation of acetaldehyde according to this process requires reducing conditions whereas the formation 120 of acetic acid therefrom requires oxidizing conditions.

125 Considering only the fact that in proportion as acetic acid is formed the concentration of the acid would increase more and more, the result in such processes would further be a disturbance of the equilibrium in the conditions necessary to arrive at the in-

dustrial result above indicated. The conditions necessary in my present invention are therefore also in contradiction with a process recently proposed in which one oxidizes 5 simultaneously or employs an oxidizer such as ferric-sulfate to prevent the reduction of the salt of mercury.

Further it has been found that the acetylene introduced should be purified, before its 10 introduction, from impurities such as sulfureted and phosphoreted hydrogen, ammonia, and the like; the first two of these on coming into the absorption liquid would form sulfur or phosphorus compounds of 15 mercury, that is to say products inactive in the absorption of the acetylene. This is the more true as the contact substance is employed in relatively small quantity, so that even if the acetylene contains a small quantity 20 of these impurities, they contribute to render the contact substance inactive very quickly.

(b). *Apparatus employed for the manufacture of acetic aldehyde.*

Glass is of course inapplicable for apparatus on an industrial scale, and in view of the volatile nature of acetic aldehyde it is difficult to employ earthenware alone; the 30 more so as strong agitation is necessary and an apparatus capable of standing pressure and heating is also necessary.

An ordinary earthenware apparatus is unsuitable for the conditions required, especially as there is risk of its breaking, and acetic aldehyde and acetylene are very volatile and inflammable.

Iron resists amalgamation, but it is attacked by acids, and in dissolving it precipitates mercury even before the conversion 40 of acetylene into acetaldehyde begins.

I have devised a way of overcoming these difficulties, making it possible to employ iron apparatus, thus rendering the apparatus safe in working, especially guarding against the danger arising from the presence 45 of acetic aldehyde and acetylene. This will now be explained.

Based on the property possessed by lead 50 of easily withstanding the action of sulfuric acid—in which lead does not dissolve but rather forms a layer of lead sulfate—I have found that by treating or heating the lead, for example in a lead-covered iron apparatus, with more or less diluted sulfuric acid, 55 preferably in presence of an oxidizing agent such as nitric acid, there is formed a layer of sulfate of lead, and (especially in presence of an oxidizing agent such as nitric acid) 60 oxid of lead mixed with sulfate of lead—which remains attached to the lead and which, even if the metallic mercury comes in contact with it, gives no amalgamation, as this layer of sulfate of lead pro-

tects the lead against amalgamation and 65 does not dissolve in the absorbing liquid.

In practice for example a cylindrical iron apparatus of any capacity, for example 1000 to 5000 liters, is constructed, having its inside covered with lead, the surface of which 70 is treated in the manner referred to, so that the layer above indicated is obtained on the lead. Likewise the stirrer provided is covered with lead coated with this layer impenetrable to the mercury.

As a measure of precaution the cover may also be similarly coated, with the exception of the shaft of the stirrer where it passes through the stuffing box, which should be very tight to prevent leakage of the vapor 80 of the acetic aldehyde.

Moreover the apparatus may be provided, for heating, with a double bottom, or it may simply be provided with a tank or bath in which water can be heated to boiling, or, 85 though with less advantage, there may be introduced into the interior of the apparatus, pipes of lead or iron pipes covered with lead on which the layer impenetrable to mercury is produced.

The employment of apparatus having parts made of lead and coated with an insoluble layer containing lead sulfate, as described herein, for carrying out the process of making acetaldehyde by passing acetylene into the herein described absorbing solution, forms the subject matter of a divisional application 229,174, filed April 17, 1918.

Less advantageously, one could use apparatus made of iron lined with stone slabs, or apparatus made of earthenware or the like, and employ therein heating or cooling pipes made of or covered with lead provided with the described layer impenetrable 100 to amalgamation.

Example.

The accompanying diagrammatic drawing shows in vertical section, an apparatus 110 suitable for practising the invention. The parts of the absorbing vessel which come into contact with the absorbing solution should be protected by the amalgamation-resistant layer as above referred to.

A indicates a cylindrical absorption vessel of iron, having a capacity of, for example, about 2000 liters, and which may be about two or three meters in height, this vessel being provided with stirrer arms *a a* 115 mounted on a shaft *b* and adapted to be rotated very rapidly by the beveled gears, *c c'* from the driving shaft *d* provided with fast and loose pulleys *e e'*. *f* indicates an agitating and spouting member likewise 120 fixed to the shaft *b* and provided with slots *f'* and spouting nozzles *f''* as known for assisting the agitation of the liquid con-

tents of the vessel. The shaft extends up through a tight stuffing box *g* in the cover *A*² of the vessel *A*. The interior wall of the vessel *A*, of the cover *A*² and of the discharge outlet piece *h* will be lined or faced with lead coated with the said amalgamation resisting layer, as will also the outside surface of the stuffing box *g*, the shaft *b* up to the point where it passes into the stuffing box, arms *a*, and the interior and exterior surfaces of the agitating member *f*, and of the inlet pipe *j*.

i indicates a pump for supplying the acetylene gas to vessel *A* by a lead pipe *j* controlled by valve *j'*. *l* indicates the outlet pipe from vessel *A*, said pipe being controlled by a valve *l'* and depending into a back pressure chamber *m* containing liquid to a depth of about 2 to 4 meters. *m'* is a relief valve for the chamber *m*. *n* indicates the discharge valve of vessel *A*.

B indicates an outer jacket or container in which the absorption vessel *A* is mounted, and serving for heating and cooling the vessel *A* by means respectively of a steam inlet pipe *p* and drain pipe *p'*, and of a water inlet pipe *q* and water overflow pipe *q'*. *p*² *p*³ indicate the controlling valves of pipes *p* *p'* and *q*² *q*³ the controlling valves of pipes *q* *q'* respectively.

In order to form the amalgamation-resisting layer on the required parts, the lead-lined interior of the apparatus and the lead-faced parts to be protected are first treated with a mixture of dilute sulfuric acid containing nitric acid, and are heated until a layer of lead sulfate has formed on the lead so that the metallic lead will not be in contact with the absorption liquid 40 when this is introduced. After the coating operation the acid liquor is run off.

The apparatus thus prepared is charged with a mixture of 850 kilos of water and 150 kilos of concentrated sulfuric acid (96-45 99% strength) to which are added 40 to 50 kilos of oxid of mercury; the whole is heated to about 80° to 100° C., until complete solution has taken place, and after cooling, at a temperature of about 35° to 40° C., 50 acetylene is introduced, being drawn by the pump *i* and forced into the absorption liquid under a superatmospheric pressure of say about $\frac{1}{2}$ atmosphere, care being taken, as before explained, to provide at the outlet side of the absorption vessel *A* the back pressure of a liquid column of about 2 to 55 4 meters height in back pressure chamber *m*, into the bottom of which the outlet pipe *l* from the absorption vessel is led, so that the pressure of this height of liquid is exerted at the outlet side.

At the commencement of the operation care is taken that the acetylene shall not pass too rapidly. During this time the white precipitate which is formed by the intro-

duction of the acetylene darkens, becomes darker and darker, and at length black or grayish black.

The liquid now possesses the greatest absorbing power for the acetylene. 70

From this moment the acetylene is introduced as much and as rapidly as possible, preferably by several pipes leading the acetylene into the absorption liquid, but always at such a rate that all the acetylene is absorbed, good agitation being maintained during the introduction. 75

After one or several hours, a very considerable quantity of acetic aldehyde has been formed, and after stopping the introduction of the acetylene, the temperature is raised gradually from about 50°-60° C., to distil off the acetic aldehyde through the pipe *s* leading to a condenser (the valve *s'* being opened and the valve *l'* closed during this operation). To avoid any loss this condenser is cooled by the brine of an ice machine, and the acetic aldehyde escaping condensation in the first condenser is led to a second vessel cooled by the brine of an ice machine. This receptacle for collecting the acetic aldehyde is further provided with a reflux condenser also cooled by the brine of an ice machine, to make sure that no loss shall occur. 95

After distilling off the greater part of the aldehyde, the temperature is lowered again to 35° to 40° C., and the introduction of the acetylene is then recommenced, and so on. These operations are repeated alternately until the absorbing power of the absorption liquid diminishes greatly or ceases, and then for finishing, (the introduction of acetylene being stopped) the liquid is heated to a temperature of 80° to 100° C. to distil off the last traces of the acetic aldehyde. In this way, after about 20 to 25 hours, more or less, of introduction of acetylene, according to the particular case, about 500 to 700 kilos of acetic aldehyde can be obtained with a yield of 90 to 95 per cent. or more, calculated on the weight of the acetylene introduced. 100 110

The residue formed is converted into oxid of mercury for reuse. As illustrating what would be the effect of making changes in the conditions of the process above set out, and outside the invention, the following may be mentioned:— 115

If in the foregoing example, instead of 15% of sulfuric acid, there is taken say more than 20% the yield of acetic aldehyde would be much smaller, and even the yield of acetic aldehyde relatively to the quantity of acetylene introduced would diminish considerably, as an appreciable portion of the aldehyde would be converted into resinous products, and at the same time the absorbing power of the contact substance, that is to say the mercury compound contained in 120 125 130

the absorption liquid would diminish. If on the other hand the quantity of sulfuric acid were reduced, for example to 4 to 5 per cent., the yield would diminish very 5 considerably, so that only about 100 to 200 kilos of acetic aldehyde would be obtained.

Again if in the above example the duration of the introduction of the same quantity of acetylene were prolonged (*i. e.* if the acetylene were introduced slowly), the yield of acetic aldehyde would be much lower, and toward the end it would not be possible to introduce all the acetylene, since it would no longer be absorbed, as the contact substance 15 would have become inactive.

If in the example 60° to 80° C. were chosen as the temperature for introducing the acetylene, a total yield of about only 100 to 150 kilos of acetic aldehyde would be obtained, with a considerable quantity of 20 resinated products, and moreover it would only be possible to introduce a restricted quantity of acetylene, as the original quantity of acetylene of the above example would 25 no longer be absorbed, even if the time were doubled for example to say 40 to 50 hours. This diminution of yield becomes progressively more pronounced as higher temperatures are used.

Again if in the foregoing example after the introduction of the acetylene at the temperature therein indicated, there were chosen for the distillation a higher temperature than 50° to 60°, that is to say if the temperature is raised directly to 80°-100° C., the yield would diminish considerably and it would no longer be possible to introduce the same quantity of acetylene as if the 35 conditions of the example above given had 40 been followed.

If in the example the acetylene were introduced in excess, so that the acetic aldehyde was carried away with it, this would involve on the one hand the loss of the 45 acetylene together with its complicated recuperation, and on the other hand the yield of acetic aldehyde would be much less, as the absorbing power of the absorption liquid would be too quickly exhausted by this excess of acetylene.

What I claim and desire to secure by Letters Patent is:—

1. In the production of acetaldehyde from acetylene, the improvement of passing acetylene into an absorbing solution containing sulfuric acid in amount between about 10% and about 15% total acid, and a mercury compound in amount corresponding to 1 to 10 per cent. of metallic mercury, 55 both calculated on the weight of the absorbing solution, while maintaining the temperature at not above 40° C. during the introduction of the acetylene, the acetylene being introduced in a weaker current at the 60 beginning, until the mercury compound in

the solution has become gray to grayish-black, indicating that the solution has about attained its maximum absorbing power, whereafter the acetylene is introduced as rapidly as possible, while avoiding excess 70 and non-absorption, strong agitation being maintained during the introduction of the acetylene, the acetaldehyde formed being distilled off at required intervals by raising the temperature to not above 50° to 60° 75 C., while interrupting the introduction of acetylene, and the temperature being thereafter again reduced to not above 40° C., for the reintroduction of the acetylene.

2. In a process for the manufacture of acetaldehyde, the improvement which comprises passing acetylene into an absorbing solution containing sulfuric acid in amount between about 10% and about 15% total acid, and a mercury compound in amount 80 corresponding to between 3 and 6 per cent. of metallic mercury, both calculated on the weight of the absorbing solution, while maintaining the temperature between 25° and 40° C. during the introduction of the 90 acetylene, the acetylene being introduced in a weaker current at the beginning, until the mercury compound in the solution has become gray to grayish-black, indicating that the solution has about attained its maximum 95 absorbing power, whereafter the acetylene is introduced as rapidly as possible, while avoiding excess and non-absorption, maintaining strong agitation during the introduction of the acetylene, distilling off the 100 acetaldehyde formed at required intervals by raising the temperature to not above 50° to 60° C. while discontinuing the introduction of acetylene, reducing the temperature to not above 40° C. for the reintroduction 105 of the acetylene.

3. In a process for the manufacture of acetaldehyde, passing acetylene into an absorbing solution containing about 10% to about 15% of total sulfuric acid, and sulfate of mercury in amount corresponding to between 1 and 10 per cent. of metallic mercury, both calculated on the weight of the absorbing solution, while maintaining the temperature between 25° and 40° C. during 110 the introduction of the acetylene, introducing the acetylene as a slow current at the beginning, until the mercury compound in the solution has become gray to grayish-black, indicating that the solution has about 115 attained its maximum absorbing power, and thereafter introducing the acetylene as rapidly as possible while avoiding excess and non-absorption, maintaining a strong agitation during the introduction of the acetylene, 120 and as soon as the acetylene ceases to be quickly absorbed, discontinuing the introduction of acetylene, and distilling off the acetaldehyde formed, by raising the temperature to not above 50° to 60° C. and 125 130

thereafter again reducing the temperature to between 25 and 40° C., and again rapidly leading in acetylene, and repeating the cycle of operations of distilling off aldehyde 5 and rapidly introducing acetylene, and finally heating the liquid to about 80-100° C., for completely removing the acetaldehyde therefrom.

4. In a process for the manufacture of 10 acetaldehyde, passing acetylene under a slightly increased pressure of about half an atmosphere into an absorbing solution containing sulfuric acid in amount not more than about 15% and not less than about 10 15 per cent. total acid, and a compound of mercury in amount corresponding to between 1 and 10 per cent. of metallic mercury both calculated on the weight of the absorbing solution, while maintaining the temperature 20 between 25° and 40° C. during the introduction of the acetylene, the acetylene being introduced in a weaker current at the beginning, until the mercury compound in the solution has become gray to grayish 25 black, indicating that the solution has about attained its maximum absorbing power, whereafter the acetylene under said slightly increased pressure is introduced as rapidly as possible while avoiding excess and non- 30 absorption, strong agitation being maintained during the introduction of the acetylene, the acetaldehyde formed being distilled off at required intervals by raising the temperature to not above 50° C. to 60° 35 C. and while interrupting the introduction of acetylene and the temperature being reduced to not above 40° C. for the reintroduction of the acetylene, substantially as set forth.

40 5. In a process for the manufacture of acetaldehyde passing acetylene under a slightly increased pressure of about half an atmosphere into an absorbing solution containing sulfuric acid in amount not more than about 15 per cent. and not less than 45 about 10 per cent. total acid, and a compound of mercury in amount corresponding to between 3 and 6 per cent. of metallic mercury, calculated on the weight of the 50 absorbing solution, while maintaining the temperature between 25° and 40° C. during the introduction of the acetylene, the acetylene being introduced in a weaker current at the beginning, until the mercury 55 compound in the solution has become gray to grayish black, indicating that the solution has about attained its maximum absorbing power, whereafter the acetylene is introduced as rapidly as possible, while 60 avoiding excess and non-absorption, strong agitation being maintained during the introduction of the acetylene, the acetaldehyde formed being distilled off at required intervals by raising the temperature to not above

50° to 60° C. while interrupting the introduction of acetylene and the temperature being reduced to not above 40° C. for the reintroduction of the acetylene, substantially as set forth. 65

6. In a process for the manufacture of 70 acetaldehyde, passing acetylene deprived of impurities such as sulfureted and phospherated hydrogen and ammonia, into an absorbing solution containing sulfuric acid in amount not more than about 15 per cent. 75 and not less than about 10 per cent. total acid, and sulfate of mercury in amount corresponding to between 1 and 10 per cent. of metallic mercury, both calculated on the weight of the absorbing solution, while 80 maintaining the temperature between 25° and 40° C. during the introduction of the acetylene, the acetylene being introduced, after the mercury compound in the solution has become gray to grayish black, as 85 rapidly as possible while avoiding excess and non-absorption, stopping the introduction of acetylene and distilling off the acetic aldehyde at required intervals by raising the temperature to not above 50° to 60° C. 90

7. In a process for the manufacture of acetaldehyde, the improvement which comprises the step of first preparing an absorbing solution containing sulfuric acid in amount not more than about 15 per cent. 95 and not less than about 10 per cent. total acid, and a mercury compound capable of reacting with sulfuric acid to form mercuric sulfate, such mercury compound being present in amount corresponding to 1 to 10 per 100 cent. of metallic mercury calculated on the weight of the absorbing solution, by heating an aqueous liquid containing said proportion of sulfuric acid and such mercury compound until the mercury compound is dissolved, and thereafter passing acetylene into the absorbing solution while maintaining the temperature at not above 40° C., the acetylene being introduced in a weaker current at the beginning, until the mercury 110 compound in the solution has become gray to grayish black, indicating that the solution has about attained its maximum absorbing power, after which the acetylene is introduced as rapidly as possible, while 115 avoiding the introduction of acetylene more rapidly than the same can be absorbed, and until the activity of the solution for the absorption of acetylene decreases, and then discontinuing the introduction of acetylene. 120

8. In a process for the manufacture of acetaldehyde, the improved method of preparing an absorbing solution containing sulfuric acid in amount not more than about 15 per cent. and not less than about 10 per 125 cent. total acid, and a mercury compound capable of combining with such acid to form mercuric sulfate, such compound being used

in amount corresponding to between 3 and 6 per cent. of metallic mercury, calculated on the weight of the absorbing solution, by heating an aqueous liquid containing said proportion of sulfuric acid and of such mercury compound until the mercury compound is dissolved, and thereafter slowly passing acetylene into the absorbing solution while the temperature thereof is maintained at not above 40° C., until the mercury

compound in the solution has become gray to grayish black.

In witness whereof I have hereunto signed my name in the presence of two subscribing witnesses.

HENRY DREYFUS.
